CLAIM

The ornamental design for battery box, as shown and described.

DESCRIPTIONFIG. 1 is a front view of a battery box showing our design.
FIG. 2 is a rear view thereof.

FIG. 3 is a left side view thereof.

FIG. 4 is a right side view thereof.

FIG. 5 is a top plan view thereof.

FIG. 6 is a bottom plan view thereof.

FIG. 7 is a perspective view thereof; and,

FIG. 8 is another perspective view thereof.

The broken lines shown in the figures are included for the purpose of illustrating portions of the battery box and form no part of the claimed design.
